CLAIM

The ornamental design for a folding pad eye as shown and described.

DESCRIPTION

FIG. 1 is a top-front isometric view of a folding pad eye; FIG. 2 is a top-front isometric view of the folding pad eye thereof;

FIG. 3 is a bottom-back isometric view of the folding pad eye thereof;

FIG. 4 is a bottom-back isometric view of the folding pad eye;

FIG. 5 is a left side view of the folding pad eye;

FIG. 6 is a left side view of the folding pad eye thereof;

FIG. 7 is a right side view of the folding pad eye;

FIG. 8 is a right side view of the folding pad eye thereof;

FIG. 9 is a section view of the folding pad eye taken along section line 9-9 as shown in FIG. 1;

FIG. 10 is a top plan view of the folding pad eye;

FIG. 11 is a bottom plan view of the folding pad eye; and,

FIG. 12 is a bottom plan view of the folding pad eye thereof.

The broken lines shown in the drawings illustrate portions of the article and environment. All broken lines form no part of the claimed design.
